HAIRPIN

William Williams, Wilkes-Barre, Pa.

Application January 6, 1956, Serial No. 557,770

6 Claims. (Cl. 132—59)

This invention relates to an improved hairpin of the bobby pin type formed of a single strand of a resilient material and which is retained in engagement with the hair by a resilient clasping action.

More particularly, it is an aim of the present invention to provide an improved construction of hairpin or bobby pin which due to novel structural features eliminates the crimps conventionally utilized in bobby pins so that the hair may be more readily engaged with or disengaged from a hairpin or bobby pin.

Another object of the invention is to provide a hairpin or bobby pin having portions which uniquely coact to cause other portions of the hairpin to be resiliently urged toward one another and whereby the latter, hair engaging portions, will grip the hair with an adequate clasping action to prevent accidental release of the hair from the hairpin.

Various other objects and advantages of the invention will hereinafter become more fully apparent from the following description of the drawing, illustrating a presently preferred embodiment thereof, and wherein:

Figure 1 is a side elevational view of the pin;

Figure 2 is a top plan view thereof;

Figure 3 is an enlarged fragmentary side elevational view of the intermediate portion of the hairpin, and

Figure 4 is an enlarged end elevational view looking toward the looped end of the pin or from left to right of Figure 1.

Referring more specifically to the drawing, the improved hairpin or bobby pin in its entirety and comprising the invention is designated generally 5 and is formed from a single elongated strand of a resilient material which may be of any desired cross sectional shape. The strand forming the bobby pin 5 is bent back upon itself substantially intermediate of its ends to provide a loop 6, constituting one end of the pin and from which project the two legs, designated generally 7 and 8. Said legs 7 and 8 are spring biased toward one another by the resiliency of the loop 6. The leg 7, as best illustrated in Figure 1, is bowed longitudinally from end-to-end thereof in a direction inwardly or toward the other leg 8.

The leg 8 includes a substantially straight portion 9 which extends from the loop 6 and which terminates in a modified V-shaped portion 10 which projects from the axis of the leg 8 toward the leg 7. The outer side of the apex 11 normally bears against a portion of the leg 7, as seen in Figure 1. A shorter arm 12 of the portion 10 extends between the apex 11 and the adjacent end of the leg portion 9 and the other longer arm 13 of the V-shaped portion 10 extends outwardly a substantial distance from the apex 11 in a direction away from the leg 7. The leg 8 includes a straight portion 14 which extends inwardly from the outer end of the arm 13 toward the leg 7 and which terminates in spaced apart relation thereto. Said arm portions 13 and 14 combine to form a V-shaped portion which is inverted relative to the V-shaped portion 10 and which last mentioned V-shaped portion, designated generally 15, like

2

the V-shaped portion 10, includes a long arm and a short arm. Thus, the arms 12 and 14 of the V-shaped portions 10 and 15, respectively, substantially correspond with one another and are disposed nearly parallel and the longer arm 13, which is interposed therebetween, constitutes an arm common to both of said oppositely facing V-shaped portions.

The leg 8, remote from the inwardly opening V-shaped portion 15 and adjacent the free end of said leg, is provided with an inwardly opening V-shaped portion, designated generally 16, including an inner shorter arm 17 and an outer longer arm 18. The arm 17 corresponds substantially to the arm 14 and the arm 18 corresponds substantially to the arm 13. Said arms 14 and 17 are disposed between the longer arms 13 and 18. The leg 8 terminates in a substantially straight terminal portion 19 which constitutes substantially a right angular extension of the other end of the arm 18, which is located remote from the arm 17. Said terminal portion 19 projects from the arm 18 in diverging relation to the terminal portion 20 of the leg 7 and combines therewith to form an outwardly flared throat 21. The terminal portion 20 preferably extends somewhat beyond the terminal portion 19, as clearly illustrated in Figures 1 and 2. The outer side of the apex 22 formed by the arm 18 and terminal portion 19 constitutes a second apex which like the apex 11, bears against a portion of the leg 7. The leg 8 additionally includes an elongated substantially straight intermediate portion 23 which extends between and merges integrally at its ends with the complementary adjacent ends of the arms 14 and 17. The V-shaped portions 10 and 15 comprise an inner crimped portion of the leg 8 and the V-shaped portion 16 and terminal 19 constitute an outer crimped portion of said leg, which crimped portions are connected by the intermediate portion 23.

From the foregoing it will be readily apparent that the legs 7 and 8 of the hairpin 5 may be readily spread apart by grasping the terminal portions 20 and 19, respectively, thereof so that a lock or other mass of hair, not shown, may be readily entered between the legs 7 and 8 and clasped tightly between the intermediate leg portion 23 and the complementary portion 24 of the leg 7, which is disposed between the apices 11 and 22 and the intermediate part of which engages said leg portion 23. When the legs 7 and 8 are thus spread apart for engaging a mass of hair, the spreading thereof occurs between the leg terminals 20 and 19 and the apex 11 and the portion of the leg 7 normally engaged thereby, so that said apex 11 will provide a stop to prevent the hair entering the closed end of the bobby pin, between said apex 11 and the loop 6. Thus, the resiliency afforded by the loop 6 will not be adversely affected by hair wedged between the legs adjacent the loop.

It will also be readily apparent that the apices 11 and 22 engage the leg 7 at points relatively near to the ends of the pin 5, as compared to the spacing between the points 11 and 22, so that in addition to the biasing action of the loop 6 tending to urge the legs 7 and 8 toward one another, the inwardly bowed longitudinal configuration of the leg 7 will be increased by contact of the apices 11 and 22 with the leg 7, so that the portion 24 thereof, disposed between the points 11 and 22, will be bowed inwardly and toward the portion 23 to even a greater extent than would occur due to the normal contour of the leg 7. Thus, the portions 23 and 24 between which the hair is gripped will be urged toward tight frictional engagement with the hair. Additionally, the portion 23 which is normally substantially straight will be bowed to some extent by contact with the portion 24 so that said portions 23 and 24 will assume more nearly conforming shapes, as illustrated in Figures 1 and 3. This

conformable shaping of the portions 23 and 24 will be augmented by the hair clamped therebetween.

Further, the apex 22 will function in the same manner as the apex 11 to prevent slippage of the hair back into the throat 21 to thus prevent accidental release of the bobby pin.

Various modifications and changes are contemplated and may obviously be resorted to, without departing from the spirit or scope of the invention as hereinafter defined by the appended claims.

I claim as my invention:

1. A hairpin of the bobby pin type formed from a single strand of resilient material comprising a first leg, a second leg and a loop portion, said loop portion defining a closed end of the pin from which said legs project and by which said legs are spring biased toward one another, said first leg being longitudinally bowed substantially from end-to-end thereof inwardly and toward the second leg, said second leg having longitudinally spaced apex portions bearing against longitudinally spaced portions of the first leg, said second leg including an elongated substantially straight intermediate portion disposed between said apex portions, end portions of which are spaced from adjacent portions of the first leg and an intermediate part of which is normally disposed in resilient engagement with an intermediate part of the first leg.

2. A hairpin of the bobby pin type formed from a single strand of resilient material comprising a first leg, a second leg and a loop portion, said loop portion defining a closed end of the pin from which said legs project and by which said legs are spring biased toward one another, said first leg being longitudinally bowed substantially from end-to-end thereof inwardly and toward the second leg, said second leg having longitudinally spaced apex portions bearing against longitudinally spaced portions of the first leg, said second leg including a substantially straight intermediate portion disposed between said apex portions, end portions of which are spaced from adjacent portions of the first leg and an intermediate part of which is normally disposed in resilient engagement with an intermediate part of the first leg, said second leg having inner and outer substantially V-shaped portions opening away from the first leg and constituting said apex portions, said second leg including inwardly opening substantially V-shaped portions interposed between the ends of said intermediate portion of the second leg and said first mentioned V-shaped portions and each having an

inner arm merging with said intermediate portion of the second leg and which is spaced from an adjacent portion of the first leg.

3. A hairpin as in claim 2, one arm of the first mentioned outer V-shaped portion constituting the terminal of the second leg and being disposed in outwardly diverging relation to the distal end of the first leg and combining therewith to form a flared entrance throat of the pin.

4. A hairpin as in claim 3, said second leg having a substantially straight portion extending from the loop and merging with an arm of the first mentioned inner V-shaped portion.

5. A pin of the character described formed from a single strand of resilient material comprising a first leg, a second leg and a loop portion, said loop portion defining a closed end of the pin, said legs extending from said loop portion and being spring biased thereby toward one another, said first leg being longitudinally bowed inwardly and toward the second leg, said second leg having longitudinally spaced crimped portions each including an inwardly extending apex, said apexes bearing against longitudinally spaced portions of the first leg for spacing other portions of the second leg, disposed between said apexes, from the first leg, said second leg having a substantially straight portion disposed between and connected to said crimped portions and spaced from said apexes and engaged by a contiguous portion of the first leg between and spaced from the ends of said straight portion.

6. A pin as in claim 5, said portion of the first leg disposed between said apexes being tensioned by contact of the apexes with the first leg for urging said first leg portion into tight frictional contact with the portion of the second leg contiguous therewith and whereby said portion of the second leg is deformed by the tension of said first leg portion into substantial conformable engagement therewith.
